FIG.1.

FIG.2.

FIG.3.

FIG.4.

FIG.5.

FIG.6.

FIG.7.

FIG.8.

FIGURE 1 is a side view of grass shears with the operating lever in the closed position, showing my new design;

FIGURE 2 is a view of the side opposite to that seen in FIGURE 1;

FIGURE 3 is a plan view thereof;

FIGURE 4 is an underneath plan view thereof;

FIGURE 5 is an end view thereof as seen from the right hand side of FIGURE 1;

FIGURE 6 is a view of the end opposite to that of FIGURE 5;

FIGURE 7 is a perspective view from above with the operating lever in the closed position, and

FIGURE 8 is a similar view to FIGURE 7 with the operating lever in the open position.

The dominant features of the design reside in the handle shown in full lines, the conventional blades being shown in broken lines.

I claim:

The ornamental design for grass shears, as shown and described.
